Ohio, a corporation of Ohio

Application June 7, 1939, Serial No. 277,826

5 Claims. (Cl. 271—2.6)

This invention relates to a mechanism for joining successive coils of metal strip, e. g., hot rolled steel strip for continuous processing such as pickling or the like.

5 The continuous treatment of strip in coils is greatly facilitated by joining successive coils end to end. Numerous methods of so joining coil ends have been employed, viz., electric flash welding, gas welding, stitching, or the like. The 10 practice has been to line up the coil ends to be joined by eye. This requires considerable time and is not very accurate. As a result, successive strips are joined at a slight angle, instead of in perfect alinement, and this causes difficulty in the cold rolling. The amount of time required 15 to line up the coil ends by eye is particularly objectionable because it frequently necessitates stopping the travel of the strip through the pickling tanks or other processing apparatus.

20 I have invented a novel apparatus for quickly alining the ends of successive coils of strip preliminary to the joining thereof as by welding. In a preferred form of the invention, I provide a plurality of pairs of side guides mounted adjacent the path of travel of the strip and adjustable toward and from the center-line of said path. The side guides are adjustable for various widths of strip by means of a motor-driven adjusting screw. I also provide means for advancing and retracting the guides through a short distance, after they have initially been set for the desired width of material, to engage the material to aline it for shearing and welding, and then free it for continuous movement through 25 the pickle line or other processing apparatus. Other novel features and advantages of the invention will become apparent during the course of the following detailed description which refers to the accompanying drawings illustrating a 30 preferred embodiment. In the drawings:

Figs. 1 and 1—A together constitute a plan view, largely diagrammatic, illustrating the apparatus usually employed at the entrance end of a pickle line with the invention incorporated 35 therein;

Figs. 2 and 2—A together constitute a view partly in section along the center-line of the apparatus shown in Figs. 1 and 1—A, and partly in elevation;

40 Fig. 3 is a side elevation of the side guides and operating mechanism therefor;

Fig. 4 is an end view showing the appearance of the structure of Fig. 3 from the left;

45 Fig. 5 is a sectional view taken along the plane of line V—V of Fig. 3;

Fig. 6 is a sectional view taken along the plane of line VI—VI of Fig. 3;

Fig. 7 is a sectional view taken substantially along the plane of line VII—VII of Fig. 3, showing parts in elevation;

Fig. 8 is a sectional view taken along the plane of line VIII—VIII of Fig. 7; and

Fig. 9 is a view partly in section and partly in end elevation along the line IX—IX of Fig. 8.

Referring now in detail to the drawings, the 10 invention is particularly adapted for use with the apparatus usually installed at the entering end of a pickle line and including a coil conveyor 10, an up-end 11 having a tilting coil holder 12 thereon whereby coils disposed on the conveyor 10 may be moved therealong, turned on their sides, and rolled into a processing uncoiler 13. A 15 roller table conveyor 14 extends from the exit side of the uncoiler 13 for supporting the strip emerging therefrom as it passes forward through 20 other apparatus to be shortly described and thence to the pickle tanks or other processing equipment.

A squaring shear 15 is disposed adjacent the 25 uncoiler 13 for removing the irregularly shaped ends of the coils C as received from the hot mill. A welder 16 is next in line and serves to join the 30 ends of successive coils after they have been sheared by the shear 15. A flash-trimmer 17 adjacent the welder 16 removes the burr or flash 35 formed during the welding. A stitcher 18 is also installed in the line of travel of the strip and is provided with clamping shoes 19. Pinch rolls 20 are provided to pull the strip through the apparatus just described and deliver it to a looping 40 pit 21 whence it is withdrawn by a pair of pinch rolls 22 through guide and leveling rolls 23 for 45 delivery to the pickling tanks. The apparatus described so far is conventional and no detailed description thereof is required for an understanding of the structure and operation of the invention.

In order to aline the ends of successive coils with the common center-line of the apparatus 50 already described, before squaring the ends of the coils or welding them together, I provide 55 guide mechanisms 24 and 25 on the entrance side of the shear 15 and similar mechanism 26 on the exit side of the shear. I further provide 60 similar mechanisms 27 and 28 on opposite sides of the welder 16 and a similar mechanism 29 on the entering side of the stitcher 18. The guide 65 mechanisms are all substantially identical in construction and arrangement except that those 70

on the welder 16 are inverted relative to the others, because of the welder construction.

Fig. 3 is a side elevation of one of the guide mechanisms as installed on the welder and shows the appearance of the other guide mechanisms inverted. The inverted arrangement of the welder guide mechanisms, however, is merely a matter of convenience and is not necessary in all types of welders.

10 Referring now more particularly to Figs. 3 through 9, a guide carrier or beam 30 extends across the conveyor 14 having feet 31 at each end adapted to rest on suitable supports 32.

15 Ways 33 are formed on opposite sides of the carrier 30 and guides 34 and 35 are slidable on said ways, being secured thereon by gibbs 36. The guides are substantially C-shaped and have wearing blocks 37 therein adapted to engage the edges of the strip on the table 14.

Equal and opposite movement of the two guides is obtained by means of rack bars 38 and 39 slidably disposed in the carrier 30 meshing with a pinion 40 journaled centrally therein, the rack bars engaging the pinion on opposite sides thereof. Bearing rollers 41 adjacent the pinion 40 hold the rack bars in engagement therewith. As clearly shown in Figs. 8 and 9, each of the guides has a lug 42 which is received in a notch near the end of one of the rack bars so that the guides and rack bars move together, the two guides moving simultaneously and in opposite directions at all times.

30 The carrier 30 has a lateral extension 43 at one end thereof provided with ways on which a base plate 44 is slidable. A motor and speed-reducer unit 45 is secured to the base plate 44 and the low speed shaft thereof is engaged by a friction coupling 46.

40 A screw shaft 47 extending longitudinally of the carrier 30 has its inner end slidably journaled in a bearing 48 formed in the carrier 30. The screw shaft is threaded through a nut 49 disposed between lugs 50 and 51 formed on the guide 34. The other end of the screw shaft is provided with a thrust bearing 52 and is engaged by the coupling 46. The bearing 52 is disposed in a seat 53 depending from the base plate 44. It will be apparent that when the screw 47 is driven by the motor reducer unit 45, the nut 49 causes the guide 34 to travel along the ways 33, the direction of motion depending on the direction of rotation of the screw shaft. Any movement of the guide 34, furthermore, is effective to cause an equal, opposite and simultaneous movement of the guide 35, by reason of the engagement of the racks 38 and 39 with the pinion 40.

60 The motor reducer unit 45, screw 47 and nut 49 constitute means for adjusting the guides 34 and 35 to the width of the material passing over the table 14. A fluid-pressure cylinder and piston 54 is secured to the carrier 30, the piston 65 having a connecting rod 55 pivoted to the slidable base plate 44 at 56. By supplying fluid under pressure to opposite ends of the cylinder 54 successively, the base plate is shifted along its ways. This movement of the base plate and 70 motor reducer unit is communicated to the guide 34 through the screw 47 and nut 49 and the guide 35 is actuated by movement of the guide 34.

75 The cylinder and piston 54 thus serve, after the guides 34 and 35 have initially been adjusted in accordance with the width of the material be-

ing handled, to advance the guides into engagement with the edges of the strip and retract them therefrom to aline the strip with the center-line of the shear, welder, etc. during the operation thereof and then free the strip for rapid travel from the uncoiler to the looping pit and pickle tanks.

Assuming that the first coil has been started through the line, it continues to unwind and move forward over the table 14 until the trailing end appears. The pinch rolls 20 are then stopped with the trailing end of the first coil on the entering side of the shear 15. Meanwhile the surplus strip accumulated in the looping pit 15 21 is continuously fed forward to the pickle line.

If the guides 34 and 35 of the several guiding mechanisms have already been adjusted to the width of the strip by operating the motors 45, the cylinders 54 of the mechanisms 26 and 27 20 are actuated to bring their guides into engagement with the edges of the strip, thereby alining the latter with the center-line of the shear 15. The fluid pressure cylinders 54 operate the guides very rapidly and at a fixed maximum pressure 25 which can be so chosen that the strip will not be buckled by engagement of the guides therewith.

While the trailing end of the first coil is firmly held in alinement with the center-line of the apparatus by the guides of mechanisms 26 and 30 27, the shear 15 is operated to make a squaring crop. After operation of the shear, the guides are retracted and the pinch rolls 20 are started and the trailing end of the first coil is advanced to proper position in the welder 16. When the strip has been stopped with its trailing end at the proper point, the guides of mechanisms 28 and 29 are actuated in the manner just described, causing them to engage the strip edges at the same points in relation to the strip end as at 40 the shear and aline the strip with the welder. It will be understood that the shear, welder and other apparatus are all set on a common center-line so that when the trailing end of coil No. 1 has been engaged by the guides of mechanisms 45 25 and 26, it is centered accurately on precisely 45 the same center-line as that on which it was centered during the shearing by shear 15.

During the advancement of the trailing end of coil No. 1 to the welder and its centering therein, 50 the second coil is placed in the uncoiler 13 and its leading end started therethrough and along the table 14. When the leading end has passed slightly beyond the shear 15, the guides of mechanisms 24 and 25 are caused to engage the strip edges, 55 thereby centering the strip accurately for crop shearing. After operation of the shear, the guides of mechanisms 24 and 25 are retracted and the leading end of the second coil is then advanced to the welder and stopped in proper relation to the trailing end of the first coil. The guides of mechanisms 26 and 27 are then actuated to re-center the leading end of the second coil with the common center-line. The ends of the two coils to be welded are thus accurately centered on the common center-line of the several units and in proper position for welding.

When the weld has been completed, the guides of mechanisms 26, 27, 28 and 29 are retracted and the welded joint connecting the two coils is forwarded to the flash-trimmer 17 for removal of the burr, after which the entire length of the coil is fed into the looping pit by the pinch roll 20, the guides of all the guiding mechanisms being retracted. When the trailing end of the coil 75

appears, the cycle of operation described above is repeated.

It will be apparent from the foregoing description that the apparatus described causes the ends of successive coils to be accurately centered for shearing and again centered on the same center-line for welding. This overcomes the difficulty experienced heretofore from welding coils together after alining them solely by eye. It also avoids the delay involved in the latter, since the operation of the guides is very rapid. It has already been pointed out that the fluid-pressure cylinder for actuating the guides into engagement with the strip edges has the advantage of high operating speed and definite control of the maximum pressure so that buckling of the strip may be avoided.

While I have illustrated and described but a preferred form of the invention, it will be recognized that changes in the construction and arrangement of the apparatus and in the operating procedure thereof, may be made without departing from the spirit of the invention or the scope of the appended claims. For example, it is possible, in certain cases, to dispense with the guiding mechanisms 24 and 26 as the mechanisms 27 and 28 may be utilized to aline the trailing end of the coils preliminary to cropping.

30 I claim:

1. Apparatus for alining strip coils end to end on a supporting table preparatory to squaring and welding, comprising a beam extending transversely of said table, side guides adapted to travel along said beam, means for traversing one of said guides across the table, means actuated by movement of said one of said guides for effecting equal, opposite and simultaneous movement of the other guide, a motor for actuating said first-mentioned means to cause substantial movements of said guides and means for shifting said motor bodily to cause minor movements of said guides.

2. Apparatus for alining strip coils end to end on a supporting table preparatory to squaring and welding, comprising a beam extending transversely of said table, side guides adapted to travel

along said beam, means for effecting equal and simultaneous movement of said guides toward and from each other, power means for actuating said means to cause substantial movements of said guides, means mounting said power means for limited movement, and means effective to move said power means, thereby effecting minor movements of said guides.

3. Apparatus for alining strip coils end to end on a supporting table preparatory to squaring and welding, comprising a beam extending transversely of said table, side guides adapted to travel along said beam, and means for shifting said guides toward and from each other including guide-adjusting means, a motor connected to said adjusting means, means mounting said motor for limited movement, and means for moving said motor to effect slight movement of said adjusting means.

4. Apparatus for alining strip coils end to end on a supporting table preparatory to squaring and welding, comprising a beam extending transversely of said table, side guides adapted to travel along said beam, a screw for adjusting one of said guides along said beam, means for communicating movement of said one of said guides to the other guide in reverse sense, a motor driving said screw, and means adapted to effect limited movement of said motor longitudinally of said screw.

5. Apparatus for alining strip coils end to end on a supporting table preparatory to squaring and welding, comprising a beam extending transversely of said table, side guides adapted to travel along said beam, a reverse-motion mechanism connecting said guides whereby movement of one causes an equal and opposite movement of the other, an actuating means connected to only one of said guides effective to adjust the guides throughout their entire range, and a single power means directly connected to only one of said guides and effective to cause only minor adjustments thereof.

DONALD A. MCARTHUR. 45
